Inventor:

United States Patent Office.

DAVID MORRIS, OF BARTLETT, OHIO.

Letters Patent No. 74,401, dated February 11, 1868.

IMPROVED IMPLEMENT FOR EXTRACTING NAILS.

The Schedule referred to in these Letters Patent and making part of the same.

TO ALL WHOM IT MAY CONCERN:

Be it known that I, DAVID MORRIS, of Bartlett, in the county of Washington, and State of Ohio, have invented a new and improved Tool for Extracting Nails; and I do hereby declare the following to be a full, clear, and exact description of the same, sufficient to enable those skilled in the art to make use of it, reference being had to the accompanying drawings, forming part of this specification, in which—

Figure 1 is a perspective view of my improved tool, and

Figure 2 is a view of the face of the tool, with a portion of the handle.

This improved tool contains several different sets of jaws, for taking hold of nails under different circumstances, combined with a hammer having a curved face.

In the drawings, A represents the handle, and B the shank of the tool, the latter terminating in a curved sharp jaw, J. Pivoted to the shank B, immediately at the base of the jaw, is a heavy metallic head, H, of the form shown in the drawings. This head is provided with a jaw, J', which operates in connection with the pivoted jaw J, as clearly seen in fig. 1. On its back it has two fixed jaws, c c, and at the inner edge of its face another pair, e e. The head is of uniform thickness, and is provided with a curved face, f, on the side opposite to the jaws c c. The outer edge of the face is about even with the outer ends of the jaws J J'.

A tool thus constructed is adapted to drawing nails, tacks, &c., from any kind of wood, whether countersunk or not, with great ease. If the nail is sunk deep into the wood, the jaws J J' or c c are to be adjusted astride of it, and a sharp blow of the hammer given to the end of the handle, or to the face f, as the case may be, sufficient to sink the ends of the jaws below the head of the nail. Then, by grasping the nail in the jaws J J', and resting the tool on the point h, as a fulcrum, the nail can be extracted with the greatest ease. It is evident that the greater the resistance of the nail, the greater the force with which the jaws will grasp it. If it is a small nail or tack that requires extraction, the V-shaped claw e e will be adapted to it. When using this claw, the tool will rest on the face f as a fulcrum, which, from its curved form and smoothness, will not be likely to injure the wood-work. This will be a particularly valuable feature when the tack or nail is to be drawn from any fine wood highly polished or painted. The face or side of the head H may be used as a hammer, for driving or straightening the nail, being adapted to such purpose by its form and the weight of the head.

The tool will often be conveniently applied by grasping it in the hand at the shank B, placing the jaws J J' in contact with the nail, and holding them together by pressing against the face f with the finger, so as to keep the jaws closed upon the nail. In this manner it will operate in a measure as a pair of pliers.

Having thus described my invention, I do not broadly claim the use of pivoted jaws J J' in connection with a handle, for I am aware that such a device has long been known and used.

What I do claim as my invention, and desire to secure by Letters Patent, is—

The implement herein described, consisting of the jaws J J', handle A B, jaws c c, claw e e, and the head H, provided with face f, the whole constructed and arranged as described, as an article of manufacture.

DAVID MORRIS.
